ABSTRACT OF THE DISCLOSURE

Mould support carriage for a centrifugal casting machine which employs two pouring troughs alternately, the carriage carrying on each side a longitudinally extending assembly of aligned channel-sectioned supports for receiving and supporting the corresponding trough while the other trough is being used for casting.

The present invention relates to machines for centrifugally casting iron pipes having a socket in accordance with the "de Lavaud" method, as described, for example, in U.S. Patent No. 1,329,295. The invention more particularly relates to the mould support carriage of machines of this type having a high output and equipped with parallel pouring troughs.

It is known that the pouring troughs or channels have great length and a small section and are subjected to high flexion due to their weight. For the purpose of avoiding an excessive sagging of the end of each trough, and in particular the end of the trough which is inoperative and at rest while the other trough is operative (since the end of the operative trough can rest on the inner wall of the centrifugal casting mould), the invention aims at providing very simple guide and support means.

The object of the invention is to provide a mould support carriage for a centrifugal casting machine wherein the liquid metal is supplied by way of one or the other of two parallel pouring troughs, said carriage carrying on each side, namely on the right and left side thereof, a longitudinally extending assembly of aligned supports for receiving the corresponding right or left trough when inoperative and at rest, said support assemblies being spaced apart transversely of the carriage a distance equal to twice the distance between the two pouring troughs.

Another object of the invention is to provide a centrifugal casting machine having two pouring troughs and equipped with said improved carriage.

Further features and advantages of the invention will be apparent from the ensuing description with reference to the accompanying drawings.

In the drawings:

FIG. 1 is a diagrammatic elevational view of a centrifugal casting machine equipped with a carriage having trough supports according to the invention;

FIG. 2 is a corresponding plan view;

FIG. 3 is an end elevational view taken along line 3—3 of FIG. 1;

FIG. 4 is a partial elevational view of one of the trough support assemblies, on a scale greater than that of FIGS. 1-3;

FIGS. 5 and 6 are cross-sectional views taken along lines 5—5 and 6—6 of FIG. 4, and

FIG. 7 is a perspective view on an enlarged scale of one trough support assembly according to the invention.

In the ensuing description, the end of any element of the machine adjacent the pouring ladle B will be termed

the "upstream" end and the end of said element remote from the ladle the "downstream" end.

In the illustrated embodiment, the invention relates to a centrifugal casting machine having a carriage A which supports internally a rotary mould or shell a (FIGS. 2 and 3). The carriage A undergoes a longitudinal movement of translation. The centrifugal casting mould a receives iron from either of two pouring troughs or passages 2 and 2a which are fed alternately by a tiltable pouring ladle B.

10 The troughs 2 and 2a are simultaneously transversely movable in translation in the known manner so that one (2a) of the troughs which has just poured metal is withdrawn laterally so that the other (2) can in turn come into action. The two troughs are parallel and supported at their upstream ends, near the ladle B, by a transverse carriage C (FIGS. 1 and 2) which turns the troughs about their longitudinal axis (known arrangement) and, further along the troughs in the downstream direction, by a second longitudinally movable carriage D which has a transversely movable slide D₁. The carriage D is connected to the upstream end of the carriage A in such manner as to move with the latter. The slide D₁ supports the troughs 2 and 2a as they are moved transversely. In particular, the slide D₁ supports the free or inoperative trough (2a) when the latter is at rest and the carriage A is at the greatest distance from the pouring ladle B (the downstream position shown in dashed line in FIG. 2).

20 According to the invention, a left and a right longitudinal assembly, E₁ and E₂, of trough supports are mounted on each side of the carriage A. The two assemblies are symmetrically disposed relative to the axis X—X of the mould a (FIG. 2) and spaced apart transversely of the latter a distance 2x which is equal to twice the distance x between the troughs 2 and 2a. The latter rest in turn on one or the other, E₁ or E₂, of said support assemblies.

25 Each trough support assembly comprises short half-sleeves 3 forming channels (FIGS. 1, 2, 4, 6, 7). For example, two half-sleeves are provided. Each half-sleeve has at its upstream end a conical flared entrance portion 4 which guides the nose of the trough as it enters the support. Each support assembly also comprises a complete sleeve 5 at the downstream end of the assembly, this sleeve having a conical flared entrance portion 6 in which the downstream end of the trough 2 or 2a is disposed when this trough is inoperative.

30 The half-sleeves 3 and the sleeve 5 are supported by brackets 7 fixed to the carriage A. They are in axial alignment and are spaced apart great distances. The interest of this arrangement will be explained hereinafter. The distance between the half-sleeve 3 adjacent the carriage D and the end sleeve 5 corresponds to the length of the trough 2 or 2a adapted to be inserted in the mould a.

35 Each support assembly E₁ or E₂ is completed by a vertical protecting wall 8 with which the half-sleeves 3 and the sleeve 5 are rigid. This vertical wall 8 is secured to the carriage A and is in the extension of the edges of the half-sleeves 3 adjacent said carriage. The length of the vertical wall 7 corresponds to the length of the troughs 1 and 2.

40 The carriage operates in the following manner: It will be assumed that the trough 2 is operative and the trough 2a inoperative.

45 As the carriage A moves towards the trough 2 from the downstream position shown in dotted line in FIG. 2 towards the position shown in full line, the trough 2a, which is in alignment with the support assembly E₂, is engaged on the first half-sleeve 3. The flared portion 4 guides the trough. Then the trough 2a is engaged on the second half-sleeve 3. Finally, the end of the trough 2a

stops inside the sleeve 5. The part of FIG. 2 in full line shows the trough 2 in operation which pours the iron into the mould while the trough 2a is at rest on its support assembly E₂.

During the pouring, the trough 2a at rest is turned upside down so as to empty the iron remaining from the previous pouring which is solidified in the form of small rods. The spaces between the sleeve 5 and the half-sleeves 3 allow these rods to drop away.

Owing to the half-sleeves 3 and the support sleeve 5, the pouring trough retains its rectilinear shape. Owing to the sleeve 5, which acts as a journal for the end of the trough the latter is well supported and guided as it is being turned over. Thus, the pouring trough is well supported and guided by each element of the assembly E and is less subject to deformations and has a longer life.

Owing to the vertical protecting wall 8, the end of the trough has no tendency to hook against projecting portions of the housing of the carriage A as the carriage moves towards the ladle B.

The conical flared portions 4 and 6 of the half-sleeves 3 and of the sleeve 5 allow the nose of the trough to engage the supports in a correct manner even if the trough is slightly distorted.

Although a specific embodiment of the invention has been described, many modifications and changes may be made therein without departing from the scope of the invention as defined in the appended claims.

Thus, an element of the support assemblies E can be constructed from a single sheet of metal constituting the vertical wall 8 one of the longitudinal edges of which is notched so as to form bent tabs. The tabs bent into the form of a U form the half-sleeves 3 and the end tab is bent completely onto itself and forms the end sleeve 5. It will be understood that this sleeve and these half-sleeves are completed by conical flared portions.

Having now described my invention what I claim as new and desire to secure by Letters Patent is:

1. In a centrifugal casting machine having a mould and two longitudinally extending transversely spaced parallel pouring troughs which are adapted to be employed alternately so that each trough is employed while the other is at rest, a longitudinally movable mould support carriage having a first longitudinally extending side and a second longitudinally extending side and on which the mould is mounted for movement with the carriage longitudinally of the trough in use for pouring metal into the mould, a first longitudinally extending assembly of aligned supports and a second longitudinally extending assembly of aligned supports respectively carried by said carriage on said first and second sides thereof for respectively receiving said pouring troughs when the corresponding trough is at rest, said support assemblies being spaced apart transversely of the machine a distance equal to twice the distance between said pouring troughs, and means for guiding the troughs onto the corresponding assembly of aligned supports.

2. In a centrifugal casting machine having a mould and two longitudinally extending transversely spaced parallel pouring troughs which are adapted to be employed alternately so that each trough is employed while the other is at rest, a mould support carriage having a first longitudinally extending side and a second longitudinally extend-

ing side, a first longitudinally extending assembly of aligned supports and a second longitudinally extending assembly of aligned supports respectively carried by said carriage on said first and second sides thereof for respectively receiving said pouring troughs when the corresponding trough is at rest, said support assemblies being spaced apart transversely of the machine a distance equal to twice the distance between said pouring troughs, each support assembly comprising short half-sleeves constituting a channel and a complete end sleeve in axial alignment with the half-sleeves, the half-sleeves and the complete end sleeve being spaced apart a great distance.

3. A mould support carriage as claimed in claim 2, wherein the end sleeve and the half-sleeves of each assembly each comprise an upstream conical flared entrance portion.

4. A mould support carriage as claimed in claim 2, wherein each support assembly comprises a vertical protecting wall with which the sleeve and half-sleeves are integral, said wall being in the extension of those edges of the half-sleeves which are adjacent the carriage.

5. A mould support carriage as claimed in claim 4, wherein the end sleeve and the half-sleeves are fastened to said wall.

6. A mould support carriage as claimed in claim 4, wherein the half-sleeves and the end sleeve consist of bent extensions of a longitudinal marginal portion of said vertical protecting wall.

7. In a centrifugal casting machine having a mould and two longitudinally extending transversely spaced parallel pouring troughs which are adapted to be employed alternately so that each trough is employed while the other is at rest, a longitudinally movable mould support carriage having a first longitudinally extending side and a second longitudinally extending side and on which the mould is mounted for movement with the carriage longitudinally of the trough in use for pouring metal into the mould, a first longitudinally extending assembly of aligned supports and a second longitudinally extending assembly of aligned supports respectively carried by said carriage on said first and second sides thereof for respectively receiving said pouring troughs when the corresponding trough is at rest, said support assemblies being spaced apart transversely of the machine a distance equal to twice the distance between said pouring troughs, and means for guiding the troughs onto the corresponding assembly of aligned supports, said supports of each assembly of aligned supports being in longitudinally spaced relation to each other so that a large part of the trough supported thereby is unobstructed by the supports when it is turned over, whereby the residual metal tipped out of the trough can fall away between the supports.
